UNITED STATES PATENT OFFICE.

AUGUSTIN KULHÁNEK, OF PRAGUE, AUSTRIA-HUNGARY.

WATER-CLOSET FLUSHING APPARATUS.

SPECIFICATION forming part of Letters Patent No. 728,470, dated May 19, 1903.

Application filed January 9, 1903. Serial No. 138,442. (No model.)

To all whom it may concern:

Be it known that I, AUGUSTIN KULHÁNEK, a subject of the Emperor of Austria-Hungary, residing at Prague VII-830, Kingdom of Bohemia, Austria-Hungary, have invented certain new and useful Improvements in Water-Closet Flushing Apparatus; and I do hereby declare the following to be a full, clear, and exact description of the invention, such as will enable others skilled in the art to which it appertains to make and use the same, reference being had to the accompanying drawings, and to the figures of reference marked thereon; which form a part of this specification.

The object of this invention is to provide a flushing device for water-closets of simple, strong, and durable construction, reliable in operation, and adapted to save water.

The invention consists in the improved flushing device, in combination with the well-known siphon and swimmer arrangements, substantially as will be hereinafter more fully described and at the end embodied in the clauses of the claim.

Referring to the accompanying drawings, in which like numbers of reference indicate corresponding parts in each of the several views, Figure 1 is a vertical section of the flushing device in a front view. Fig. 2 is an axial vertical section of the same object in a side view. Fig. 3 is a sketch of the same object, on a smaller scale, as mounted in the siphon or flushing-pipe, showing the usual siphon-tank 1 on the top.

The usual siphon 2 inside the tank 1 is connected with the flushing-pipe 3, in which is interpolated the flushing device. This consists of a chamber or receptacle 4, the rear side of which forms a bearing for the horizontal shaft 5, while in the front a second bearing is provided in support 18. The front of chamber or receptacle 4 is closed by an appropriate covering. Upon the shaft 5 is fulcrumed eccentrically the bucket 6, having its center of gravity on one side of the axis 5, while on the opposite side a secondary bucket 7 is fastened onto the bucket 6. The smaller or secondary bucket 7 is calculated so as to equalize and counteract the weight of the chief bucket 6 if both are filled with water;

but the secondary bucket 7 is provided on its bottom with an opening 8, by which all the water which it would contain flows out in more or less time, and the bucket 6 would have 55 overweight on the opposite side if it is filled with water. It is provided with a butt or the like 9 on its top, which abuts against a tooth 10 if there is water in 6 and none in 7, said overweight drawing in this case the butt 9 60 against the corresponding side of the tooth 10, which keeps it in its position as long as the tooth 10 is not withdrawn. Tooth 10 can swing, but only in one direction, around a pin 11, which is parallel to the axis 5. Referring 65 to Fig. 1, it can pivot from left to right, but not from right to left. The perpendicular piece 12, in which the tooth is pivoted, can turn on a pin 13, which also is horizontal, but perpendicular to pin 11. Piece 13 can be 70 turned out of its normal position by means of a push-button 14 or the like device from outside. This pulls tooth 10 aside, so that butt 9 is free to proceed on its way if the overweight of the filled bucket 6 turns it. It is 75 evident that in this case the bucket turns around and empties its contents into the flushing-pipe 3. The downturned bucket 6 abuts below into the fixed piece 15, limiting its throw, and turns back again, being free from 80 its overweighing water. A counterweight 16 is fastened to it on the side which is opposite to the fulcrum of 6 for the purpose of assuring its return into the neutral position, in which, if filled with water, it is held fast by 85 the said tooth 10, which yields in one direction, allowing the butt 9 to catch it, but does not let it free in the opposite direction, except if it is pushed aside by pushing the button 14, as before said. In the meantime the water 90 flushing from the bucket 6 down to the flushing-pipe 3 forms a sucking-piston in the latter and sucks water from the tank 1 through its siphon 2, which continues, therefore, to flush down as long as the provision of water in the 95 said tank allows and as long as no air comes into the siphon. This flush of water falls over the division-wall 17 and fills both the chief bucket 6 and the secondary bucket 7. The buckets 6 and 7 cannot be emptied as 100 long as this flush lasts, and this cannot cease as long as the inlet of the siphon 2 is dipped

in water. The level of the water in the tank 1 sinks speedily, and as soon as the inlet of the siphon is uncovered the flush ceases completely and tank 1 begins to fill itself anew, 5 which takes place in the known way. The water from the secondary bucket 7 flows off through the small opening 8 in its bottom. Up to this moment no pushing of the button 14 could have produced a new flushing, be- 10 cause as long as the secondary bucket 7 is filled with water no overweight takes place on the opposite side. It would have been, therefore, of no effect if some person would try to produce flushes repeatedly by pushing 15 the button 14, as one would be obliged to hold this button down the whole time till after the completed flush all the water from the secondary bucket 7 would flow out through the small opening 8 in its bottom. The nat- 20 ural consequence is a great saving of water, because its flushing will surely not be unnecessarily repeated, nor can it be made to last practically longer than the time for which it has been calculated.

25 One needs, therefore, only to push the button 14 in after each use of the water-closet and then let it spring back again. Then the flush takes place instantly and regularly. Should for any reason the action of the device 30 cease, a single filling of the tank 1 and of the bucket 6 with water would suffice to make it play again. The bucket will right itself almost instantaneously after dumping or before the water from above enters the cham- 35 ber 4; but if the water is flowing through the chamber it is deflected by the wall 17, so that the tendency is to right the bucket.

Should in any case a continuous flushing 40 be desirable, then the swimmer in the tank 1 can be held up or one would in any other known way have to provide for continuous supply of water.

It will be understood that tank 1 or any 45 other device for providing the water as required for the flushing can be placed any-

where, either in the same locality with the water-closet or outside the same.

It is obvious that various alterations can be made without changing the scope of my invention. Therefore I do not intend to limit myself to the precise construction shown and described; but

What I claim as new, and desire to secure by Letters Patent, is—

1. The combination, in a flushing device, 55 of a flushing-pipe, a chamber in said pipe, a tilting bucket pivoted in said chamber, an auxiliary receptacle on one side of said bucket, a drain for said receptacle, a counterweight adapted to return said tilting bucket to nor- 60 mal position, a stop on said bucket to hold it in upright position, a pivoted catch for said stop, and means for throwing said catch out of engagement.

2. In a flushing device for water-closets and 65 the like, the combination of a vertical flush- pipe, a chamber in said pipe, a tilting bucket pivoted in said chamber, adapted to turn in discharging toward one side of the chamber, an auxiliary bucket secured to said bucket 70 on the side opposite to its discharge side, and adapted to hold sufficient water to balance said tilting bucket when both are filled, a minute discharge for said auxiliary bucket, a counterweight adapted to return the bucket 75 to normal position, a stop on said bucket, a pivoted catch for said stop, a plunger oper- ated by a push-button for disengaging said catch and stop, and a deflecting-wall in said chamber beneath the inlet-orifice adapted to 80 deflect the water toward the side of the cham- ber opposite to that toward which the bucket tips.

In testimony whereof I affix my signature in presence of two witnesses.

AUGUSTIN KULHÁNEK.
